DESIGN FOR A CLUB HOUSE FRONT OR THE LIKE

Nellie Renée Liddle, New York, N. Y.

Application October 10, 1933. Serial No. 49,442

Term of patent 14 years

To all whom it may concern:

Be it known that I, NELLIE RENÉE LIDDLE, a citizen of the United States, residing at 330 East 35th Street, in the Borough of Manhattan, city of New York, county of New York and State of New York, have invented a new, original, and ornamental Design for a Club House Front or the like, of which the following is a specification, reference being had to the accompanying drawing, forming a part thereof.

The flower box elements shown on each side of the front are an integral part of the design.

I claim:

The ornamental design for a club house front or the like as shown and described.

In testimony whereof I have signed this specification.

NELLIE RENÉE LIDDLE.
